UNITED STATES PATENT OFFICE.

WILLIAM R. GORRELL, OF ALHAMBRA, AND HENRY BARKSCHAT, OF LOS ANGELES,
CALIFORNIA.

RAIL-FASTENING DEVICE.

1,402,760.

Specification of Letters Patent. Patented Jan. 10, 1922.

Application filed June 14, 1921. Serial No. 477,500.

To all whom it may concern:

Be it known that we, WILLIAM R. GORRELL and HENRY BARKSCHAT, citizens of the United States, residing at Alhambra and 5 Los Angeles, respectively, in the county of Los Angeles and State of California, have invented certain new and useful Improvements in Rail-Fastening Devices; and we do declare the following to be a full, clear, 10 and exact description of the invention, such as will enable others skilled in the art to which it appertains to make and use the same.

This invention relates to an improved rail 15 fastening device, and has for its principal aim to provide a structure embodying novel spike holding means which is such that it permits the spike to be moved closer to or further from the rail to accommodate rail 20 base flanges of various widths.

Another object of the invention is to generally improve upon devices of this class by the provision of one of extreme simplicity and durability which further embodies a 25 novel and separate fastener of the rotary type which includes a rail engaging head and an eccentrically disposed shank which when rotated will position the head at various points to accommodate rail base flanges 30 of various widths.

A further object of the invention is to provide a novel rail fastening device which is such that it will permit the usual wooden tie to be dispensed with, since the improved 35 device can be embedded in a reinforced concrete tie, or sleeper anchored in the ground, or secured in place in any suitable way.

Other objects and advantages of the invention will be apparent during the course 40 of the following description.

In the accompanying drawings forming a part of this specification and in which like numerals are employed to designate like 45 parts throughout the same:

Figure 1 is an elevational view, with parts broken away and shown in section, of a rail fastening device constructed in accordance with our invention, showing the rail in position thereon.

Figure 2 is a top plan view of the device with the top flange broken away to disclose the construction and arrangement of parts more clearly.

Figure 3 is a detailed perspective view 55 of the rail supporting beam.

Figures 4 and 5 are top plan views of the sections or members which constitute the spike holding device.

Figures 6 and 7 are side elevational view 60 of said members.

Figure 8 is a detailed view showing an additional fastening device associated with the beam and rail base flange.

Figure 9 is a top plan view of the addi- 65 tional fastening device.

Figure 10 is an elevational view thereof.

Referring to the drawings wherein the preferred embodiment of the invention is specifically shown, the numeral 1 designates 70 a rail supporting member which is preferably in the form of an I-beam. At this point, we wish to direct attention to the fact that there is associated with this I-beam, a pair of spike holding members or clamps which 75 are designed to be positioned for co-action with the opposite edges of the rail base. Since these members are duplicates of one another, the description will be written in the singular, it being understood that such 80 terms apply to all like parts. Proceeding, it is to be said that the web 2 of the beam is provided with a vertical slot 3 near one end, while the upper flange 4 is equipped with a substantially square opening 5 at 85 this end of the slot, the base flange 6 being equipped with a smaller opening 7 at the lower end of the slot. A spike holding device or clamp already referred to, is designated as a whole by the numeral 8, the same 90 being intended to be removably held in said slot and openings in the supporting member 1. It is deemed advisable that it be pointed out here that it is not desired to be restricted to using the particular kind of rail 95 support shown with the exact type of spike holding device. However, the structure shown and described is preferred. Referring again to the spike holding device 8, and speaking broadly, it is to be stated that 100 it is equipped with an opening 9 for reception of a headed spike 10, this opening being disposed eccentrically with respect to the true axis of the device, so that by reversing the latter, the opening 9 will be 105 positioned closer to or further from the rail base flange to enable the spike to be effectively engaged with flanges of various widths

as before indicated. While the member 8 may be constructed in various ways, it is preferably made up of sections 11 and 12, the last named of which is considerably 5 smaller than the other one, both sections being formed in their outer remote faces with channels 13 for reception of the adjacent edges of the web 2. The sections are also formed on their inner faces with larger 10 channels 14 which form the aforesaid spike receiving opening 9. It is to be noted that the bottoms 5 of the channels are convex in one instance and concave in another instance, as indicated at 15 and 16, thus rendering the 15 opposed walls of the spike receiving opening irregular so that when the spike 10 is driven into this opening, it will conform to the irregular walls thereof and thus be more effectively secured in place and held against 20 possible displacement. As before indicated, the sections 11 and 12 can be easily and readily removed from the slot 3 and openings 5 and 7 to change their positions, whereby the position of the spike receiving opening 25 will be likewise changed to vary the position of the spike. It is to be pointed out here, that when the spikes are driven between the sections of the holding device, the latter are forced apart and caused to 30 tightly engage the vertical edges of the slot 3, thus holding them in place and in turn holding the spike in place. Note is to be made of the fact that the inner adjacent edges of the sections 11 and 12 are inclined 35 in opposite directions as indicated at 17, this particular construction being employed since it facilitates insertion and removal of said sections from the openings and slots in the rail supporting member 1. With the 40 edges truly vertical or straight, considerable difficulty would be encountered in assembling these sections in their proper places. The sections 11 and 12 in addition to embodying the aforesaid constructional features, are equipped on their lower ends with extensions 18 which are designed to extend into the opening 7 to prevent lateral displacement of these ends. Furthermore, in order to limit the downward movement of the 45 sections when being assembled for use, they are equipped in the bottoms of their channels 13 with shoulders 19 designed for coaction with shoulders 20 on the vertical edges of the aforesaid slot 3. Since the 50 lower ends of the sections rest on the opposite sides of the opening 7, they serve, in conjunction with the shoulders 19 and 20, to limit the downward movement of the sections. Attention is here directed to the fact 55 that the upper portions of the bottoms of the channels 13 are gradually tapered as indicated at 21 and the edges of the web on opposite sides of the slot 3 are likewise inclined as indicated at 22. Thus, when the 60 spike is driven into its receiving opening 9, 65

it is wedged in place and there is little or no chance of the sections becoming accidentally pulled out of place.

While the aforesaid construction may be sufficient for effectively connecting the rail 70 with its supporting member, we prefer to make use of novel retaining means designated by the numeral 23, the latter in its preferred form comprising a substantially square head 24 equipped with an eccentrically disposed integral shank 25 designed to extend through a circular hole 26 in the flange 4 and being equipped with a shoulder portion 27 to rest on the upper face of the flange as indicated in Figure 8. By this arrangement, it will be seen that rotation of the member 23 will position the head for engagement with rails having base flanges of various widths. In order to lock the member 23 in place, the shank thereof is 85 equipped with diametrically opposite keys or ribs 28 to be passed through correspondingly located notches 29 in the flange 4. It is understood that by registering the ribs with the notches, the locking member 23 can 90 be removed or inserted from or to its opening 26, after which by turning it, the ribs will be moved out of registry with the notches and the device locked in place.

In use, two of the rail supporting beams 95 1 will be positioned opposite one another to accommodate and partially support the two rails which serve to form the track. Any suitable means may be employed for tying these members together. If desired, the 100 members can be anchored directly in the ground, or they can be embedded in a concrete tie or sleeper (not shown) as suggested in the aforesaid patent. In the drawings, the inclined inner edges 17 of the sections 11 and 12 which are employed for forming the aforesaid spike holding means, are inclined toward each other, thus positioning the spike receiving openings at a certain distance apart. If it is desired to 110 change the positions of these openings to accommodate rails of smaller or larger sizes, this may be done, as before stated, by removing the sections 11 and 12 and reversing their position. Furthermore, the additional locking means 23 for the rail may be 115 likewise adjusted to accommodate the particular size of rail to be used.

A careful review of the foregoing description taken in connection with the accompanying drawings, will be sufficient to 120 enable persons skilled in the art to which the invention relates to obtain a clear understanding of the same. Therefore, a more lengthy and detailed description is thought 125 unnecessary.

Since probably the best results can be obtained with the construction and arrangement herein shown and described, this is 130 taken as a preferred embodiment of the in-

vention. However, slight minor changes coming within the scope of the subjoined claims may be resorted to.

We claim:

5 1. The combination with a rail support having an opening therein, of a removable spike lock having an eccentric spike receiving opening which may, by reversing the lock, be positioned to dispose the spike closer to or further from the rail base flange to accommodate flanges of various widths, and co-acting means between the lock and support to hold the former in place.

10 2. The combination with a rail supporting member having an opening therein, a removable spike locking device arranged in said opening, being made up of a pair of spaced sections having channels in their inner faces forming a spike receiving opening, opposed walls of the latter being irregular, and a spike driven into said opening, the head thereof being intended to engage the rail base flange.

15 3. The combination with a rail seat of the I-beam type having a slot formed in its web and an opening in its upper flange at the adjacent end of the slot, a removable spike locking device extending downwardly through said opening and said slot, being composed of a pair of closely spaced sections having channels formed in their opposite faces, the inner opposed channels forming an opening for reception of a spike, the remaining channels receiving the adjacent edges of said web therein, thus holding the sections against lateral displacement, and a headed spike arranged in the opening in the latter, having its head positioned for engagement with the rail base.

20 4. The combination with a rail seat of the I-beam type, having a slot formed in its web and an opening in its upper flange at the adjacent end of the slot, a removable spike locking device extending downwardly through said opening and said slot, being composed of a pair of closely spaced sections having channels formed in their op-

posite faces, the inner opposed channels forming an opening for reception of a spike, the remaining channels receiving the adjacent edges of said web therein, thus holding the sections against lateral displacement, and a headed spike arranged in the opening in the latter, having its head positioned for engagement with the rail base, the lower flange of said rail seat having an opening formed therein at the lower end of said slot into which the lower ends of said locking sections extend, the inner edges of the latter being inclined to facilitate insertion and removal, and the sections and seat having co-acting shoulders to limit downward movement of sections.

25 5. A rail seat or support of the I-beam type having a slot formed in its web and relatively small and large openings formed in its lower and upper flanges respectively and communicating with said slot, the slot being gradually increased in width from its upper end toward its center to form a shoulder and being adapted to receive a spike locking device.

30 6. A movable spike locking device adapted to be placed in an opening of a rail seat being composed of a pair of closely spaced sections or members having channels formed in their opposite faces, the inner opposed channels forming an opening for reception of the spike, the remaining channels being adapted to receive the edges of the web of the rail seat therein to hold said sections against lateral displacement.

35 7. The structure set forth in claim 6, the opposed walls or bottoms of the inner channels being irregular so as to crook or bend the spike when driven therebetween and the bottoms of the outer remaining channels being tapered from their upper ends toward their centers to provide shoulders as and for the purpose described.

40 In testimony whereof we have hereunto set our hands.

WILLIAM R. GORRELL.
HENRY BARKSCHAT.
